(57) **CLAIM**

The ornamental design for multiple showerhead manifold, as shown and described.

DESCRIPTION

FIG. 1 is a front elevational view of a multiple showerhead manifold with a diverter valve showing my new design, the rear elevational view being identical;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view of a multiple showerhead manifold without a diverter valve showing my new design, rear elevational view being identical;

FIG. 7 is a right side elevational view thereof;

FIG. 8 is a left side elevational view thereof;

FIG. 9 is a top plan view thereof; and,

FIG. 10 is a bottom plan view thereof.
